UNITED STATES PATENT OFFICE.

JEAN MARIE JOSEPH BAUDOT, OF ROUBAIX, FRANCE.

APPLICATION OF ELECTROLYSIS TO SCOURING AND SQUEEZING MACHINES.

No. 895,144.

Specification of Letters Patent.

Patented Aug. 4, 1908.

Application filed March 28, 1905. Serial No. 252,474.

To all whom it may concern:

Be it known that I, JEAN MARIE JOSEPH BAUDOT, a citizen of the French Republic, residing at Roubaix, in the Department of 5 Nord, France, have invented a new Application of Electrolysis to Scouring and Squeezing Machines, of which the following is a specification.

In cloth finishing, the scouring and washing processes after fulling and bleaching, require quite a long time, much careful handling and a large supply of water. Moreover, through lack of practical means for recovering them, the oil and fatty acids or soap 10 which is formed or added, pass away with the waste wash-liquor, giving rise to serious losses. Moreover, there are often found in the cloth and particularly after treatment in "rope" form, traces of fatty acids or soaps 15 which produce, when the cloth is being dyed, faults in the nature of spots, stains or shades, which are very prejudicial. Also the fact that the cloth is kept for a prolonged time under a rolling action when in the bath, 20 entails considerable wear, followed by a very noticeable loss in weight.

The present invention relates particularly to the treatment of the cloth after the scouring, fulling and bleaching processes, the important principle involved consisting in the treatment of the cloth by an electric current, which is used for penetrating, reducing and extracting the soapy film formed as above-mentioned. In addition to this, I aim to 30 35 cover the fatty magma having a semi-solid consistency, and resulting from the soapy matters extracted from the cloth.

With these objects in view, my invention consists in the features of construction and 40 combination as hereinafter set forth and particularly pointed out in the appended claims.

In the drawings, Figure 1 is a cross sectional view of a part of the squeezing machine together with the electrolytic vat situated at the inlet end of the plant. Fig. 2 is a 45 plan view of the same.

Referring to the drawings in which like parts are designated by the same reference sign, *a* is the cloth to be squeezed, and *b b'* 50 are movable rollers of wood or other suitable material which guide the cloth in its passage through the electrolytic vat *e* having plates or electrodes *d*. *c c'* are the squeezing rollers acting on the cloth after the same has passed 55 through the vat. The vat may be supported in any suitable way, for example, by the

frame or standard *f*. After the cloth has passed through the vat, it enters the tension device *g* of the squeezing machine *X* which imparts certain resistance to the cloth in its 60 passage in a manner sufficiently well-known, and which need not be described.

By the present method of treatment, a piece of cloth is taken after treatment in the fulling or scouring machine and before being 65 washed, that is to say, containing all the soap with which it has previously been impregnated, and its end is carried around the movable rollers *b b'* of the elevated vat *e*, placed in front of the squeezing machine. After 70 having made the circuit, the cloth is received by the squeezing machine *X*, and passes through the first compartment thereof by ascending and descending over the inside rollers *Y' Y² Y³* till it reaches and engages with 75 the first two squeezing rollers *Z Z'* covered with india rubber.

The pieces of cloth are successively passed through the apparatus being fastened end to end in a continuous series so as to act like 80 a continuous web, and secure a continuous operation of the squeezing machine.

Before starting the machine care must be taken that the electrolytic vat be provided with the required quantity of water containing carbonate of soda or potash to insure the proper action of the electrolytic plates. The quantity of liquid is kept practically constant by replenishing it as it is consumed. The effects produced: When the cloth passes 85 through the electrolytic vat, and the current is permitted to traverse the electrolyte, the latter is partially decomposed and weak alkaline products are liberated throughout the same, and particularly in the body of the 90 fabric in which the current is greater by virtue of the greater resistance. Inasmuch as the current is bound to traverse every particle of the cloth, it is insured that all the fibers are acted upon. By this action there 95 is produced, 1. A weak caustification of the alkalis, and the forming upon the cloth of a more complete soap, there being previously only a coarse soapy film. 2. By the attraction of the freed salts with the elimination of 100 gelatinous matters, waste fibers, dust and other small impurities which are kept in the yarn or material of the cloth and which are carried away with the salts thus formed, the action of scouring is quite completed, and 105 when the pieces of cloth engage between the first pair of squeezing rollers, their compress- 110

ing action absolutely removes and throws back into the first compartment the soapy matter already substantially solidified and gathered in a film on the surface of the cloth.

5 When the first compartment of the squeezing machine becomes sufficiently filled with the soapy sludge to have its cylinders and also the cloth partly bathed in it, the surplus of the said soapy sludge is led into the electrolytic recovery vat conveniently situated for this purpose. The pieces of cloth thus successively pass from the first compartment in the squeezing machine, and then are submitted to a second scouring which absolutely insures the completion of the action. There is no danger of incomplete scouring which has been the cause of many difficulties and annoyances in dyeing, chiefly when dealing with cloth which has been heavily oiled. Moreover, the method enables shortening to a considerable extent, the time ordinarily spent over the scouring and washing processes, after the fulling and bleaching processes. As a result of the facility with 25 which the soapy matters are precipitated in the first compartment, the second compartment gets so little of such matters, that the scouring of the cloth is effected well enough to allow the third compartment to be filled 30 with a large supply of running water for washing, which is in most cases quite sufficient for the last rinsing of the cloth before being dyed.

The electro-chemical phenomena whose influences have already come into play at the beginning of the operation, again come into action for recovering the fatty substances which compose the largest portion of the soapy wash-liquor led by the overflow from 35 the first compartment of the squeezing machine to the electrolytic vat connected to the dynamo. These alkaline products acting as electrolytes are decomposed in the said vat, as a consequence of the decomposition of the 40 alkaline salts. The alkaline salts are precipitated, the fatty acids depositing upon the surface of the metallic plates constituting the 45 electrolytic system of the vat or rise to the

surface of the liquor where they are easily removed. They may be afterward treated for 50 removing the excess of water which they contain. Such fatty acids still contain impurities, which are removed by submitting them to the action of a press heated by steam after which they come out clarified and pure 55 enough to be either used again for making soap or sold to the trade. The treated magma gives out from 50 to 55% in weight of fatty acids.

Having now particularly described and ascertained the nature of my said invention, and in what manner the same is to be performed, I declare that what I claim is:—

1. The process of washing fabrics which consists in guiding the fabric through a 65 trough containing an electrolyte capable of liberating an alkaline product when traversed by a current, passing a current through said electrolyte and through the fabric, whereby said alkaline product is liberated 70 within the fabric, then directing the fabric through squeezing or wringing rolls to expel the sludge and products therefrom, passing the fabric through a second trough containing an electrolyte of the character above described, sending a current through said second electrolyte, again passing the fabric through squeezing or wringing rollers, and finally cleansing the fabric in running water. 75

2. The process of washing fabrics free of 80 soap and similar products which consists in guiding the fabric through a trough containing a solution of an alkaline carbonate and a pair of electrodes, the cloth traversing a path between said electrodes whereby the current 85 traverses the cloth, and finally squeezing the fabric to expel the electrolytic products therefrom.

In testimony whereof I have signed my name to this specification in the presence of 90 two subscribing witnesses.
